(57) CLAIM

The ornamental design for a scoreline pattern for golf club head, as shown and described.

DESCRIPTION

FIG. 1 is a perspective view of a scoreline pattern for golf club head;

FIG. 2 is a rear elevational view thereof;

FIG. 3 is a top plan view thereof;

FIG. 4 is a toe end view thereof; and,

FIG. 5 is a heel end view thereof.

The broken line showing is for illustrative purposes only and forms no part of the claimed design.
